LOCK

Burnie J. Craig, Los Angeles County, Calif.

Application December 18, 1950, Serial No. 281,285

7 Claims. (Cl. 70—264)

This invention relates to a lock.

The general object of the invention is to provide an improved vehicle door lock by means of which one or more of the doors of a motor vehicle may be held securely in closed and in locked condition.

A more specific object of the invention is to provide a novel coincidental door locking system for locking a plurality of doors wherein novel locking means is employed.

Another object of the invention is to provide a door lock wherein an actuating member is movable to locked and unlocked position to release a door bolt and wherein novel means is provided by means of which closing of the door will either unlock the door if the parts are locked or permit the door to remain locked if it is closed while the parts are in locked condition.

Another object of the invention is to provide a novel latch bolt releasing means.

Another object of the invention is to provide a novel push button operated door lock.

Another object of the invention is to provide a novel handle assembly.

Another object of the invention is to provide a novel dovetail member.

A further object of the invention is to provide a novel vehicle speed controlled door lock.

Another object of the invention is to provide a novel vehicle speed controlled coincidental door locking system.

Other objects and advantages of the invention will be apparent from the following description taken in connection with the accompanying drawings, wherein:

Fig. 1 is a fragmentary elevation showing a portion of a vehicle door with the lock mounted thereon;

Fig. 2 is a view similar to Fig. 1, showing the other side of the lock;

Fig. 3 is an enlarged sectional view taken on line 3—3, Fig. 1;

Fig. 4 is an enlarged sectional view taken on line 4—4, Fig. 1;

Fig. 5 is an enlarged sectional view taken on line 5—5, Fig. 1;

Fig. 5A is an isometric view showing the locking arm;

Fig. 6 is an isometric view of the actuating member;

Fig. 7 is an isometric, schematic view, showing the coincidental mechanism;

Fig. 8 is an enlarged sectional view showing the actuating member and associated parts;

Fig. 9 is a top plan view, showing the handle assembly;

Fig. 10 is an isometric view, showing the dovetail construction;

Fig. 11 is a view similar to Fig. 8, showing a modification and

Fig. 12 is an enlarged sectional view taken on line 12—12, Fig. 11.

Referring to the drawing by reference characters, the invention is shown as embodied in a vehicle door latch which is indicated generally at 10. As shown the latch includes a body 11, adapted to be secured to a vehicle door 12. The body 11 includes a flange 13.

The body 11 supports a rotatable shaft 14 which, on the outer face of the base has a bolt 15 fixed thereon and at the inner face has a ratchet member 16 fixed thereon.

The rotary bolt 15 extends through an aperture in the door 12 and coacts with a strike member 17 which has teeth 18 thereon and 17 is secured to the door pillar

2

19 by fastening members 20. The rotary bolt includes teeth 21 which engage the teeth 18.

The ratchet 16 is adapted to be engaged by an ear 22 on a dog 23 which is shown as pivoted at 24 to the body 5 11. The dog is engaged by a spring 25 mounted on a fastening member 26. The dog is thus normally urged to engaged position against stop 27.

The dog 23 is shown as adapted to be rocked by a crank 28 mounted on a shaft 29. The crank 28 is adapted to be actuated by a remote control member 30 on the inside of a door. The remote control member 30 may be actuated by an inside handle (not shown).

The crank 28 includes an arm 31 which is disposed under an ear 32 on the dog 23. When the crank 28 is 15 rocked the arm 31 will raise the ear 32 to rock the dog and free the bolt 15.

The dog 23 also includes a downwardly extending arm 40. The arm 40 has a slot 41 therein. The slot 41 is open towards the left in Figs. 1 and 8 and includes a stepped portion 42 forming a shoulder 43. Above the shoulder 43 the slot is elongated at 44 and includes an inclined portion 45, another inclined portion 46 and a downwardly facing shoulder 47.

Above the arm 40 a rotatable and axially shiftable actuating member 48 is disposed. The actuating member is shown as integral and includes an intermediate plane portion 49 and a cylindrical end portion 50 disposed adjacent to the flange 13. The actuating member also includes a cylindrical portion 51 which is co-axial with the portion 50. The portion 51 is engaged by bent up tongues 52 on the lock body 11. The portion 51 is disposed adjacent the outer face of the door and adjacent to a release member indicated generally at 53. The release member 53 is in the nature of a handle and includes a body 54 with a finger grip portion 55 thereon.

The body 54 has a chamber 58 therein in which tumblers 59 are arranged. The construction includes a closure 60, which is non-rotatable and which supports a non-rotatable sleeve 61. The tumblers 59 are rotated in sequence in the usual manner by a dial member 62 which has a key 63 thereon fitting in a keyway 64 in one of the tumblers 59. A spring 65 normally urges the dial member 62 outwardly. Within the sleeve 61 a lock barrel 66 slides. The lock barrel 66 includes a finger-tip portion 67 which projects for operation by a finger-tip. A spring 68 normally urges the push button 67 outwardly. The lock barrel includes a ball clutch 69 which, when the tumblers are codified, releases the ball to permit rotation of the lock barrel 67.

Details of the ball clutch and the tumbler lock are fully disclosed and claimed in applicant's co-pending application, Ser. No. 185,411, filed September 18, 1950, and a further description of the clutching arrangement is deemed unnecessary.

The lock barrel supports a core 70 which is rotatable in the barrel when a proper key 71 is inserted and rotated. The core member has a forwardly projecting tongue 72.

The shaft 29 which supports the crank 28 is mounted 60 on a bracket 75 which may be spot welded as at 76 to the flange 13.

Remote from the pivot 29 the bracket 75 has an outwardly directed cylindrical portion 77 which is integral therewith. The portion 77 receives the cylindrical portion 50 on the actuating member 48. Thus the actuating member is supported at one end by the portion 77 and at the other end by the tongues 52 bent from the base 11. Adjacent to the cylindrical portion 51 the actuating member includes an integral end portion 78 which is circular in shape. The portion 78 is provided with an accurate slot 79 through which the tongue 72 on the lock barrel core 70 is arranged.

When the push button 67 is pushed inwardly the core 70 will be advanced and will engage the end 78 on the actuating member 48 and will move the actuating member to the right in Figs. 1 and 8.

When the parts are in unlocked condition a tongue 80 struck from the actuating member intermediate portion will engage the shoulder 43 and will move the shoulder and consequently the dog 23, thus moving the ear 22 from engagement with the ratchet 16 to thus release the bolt.

When the actuating member is rocked about the axis of the portions 50 and 51, the tongue 80 will move into the portion 44 of the slot when the push button is operated and thus there will be no engagement between the tongue 80 and the shoulder 43 and thus the actuating member will not move the dog and therefore there will be no bolt release. When the door 12 is closed when the actuating member 48 is in locked position, the bolt 15 will engage the strike member 17 and the bolt will be turned so that one of the teeth on the ratchet 16 will engage the ear 22 of the dog 23 and will rock the dog so that the shoulder 47 on the dog will engage the tongue 80 on the actuating member and thus will rotate the actuating member so that it moves to unlocked position.

When the door is closed when the actuating member is in locked position, inward movement of the push button 67 will move the actuating member to the right in Fig. 1 and this movement will also cause the tongue 80 to be moved out of the path of the shoulder 47, so that this shoulder will not rock the tongue 80 and thus the actuating member will remain in locked position.

In order to move the actuating member about its axis from locked to unlocked position the end portion 78 of the actuating member is provided with a slot 79 which has converging upper and lower walls 86 and 87. The tongue 72 fits in the slot 79 and when the tongue 72 is rotated as by operation of the key 71 the actuating member will be moved to and from locked position. When the actuating member is in locked position as shown by the broken lines as in Fig. 1, the wall 86 of the slot 79 will engage the tongue 72 and when the key is turned it will rock the tongue, thus turning the actuating member to unlocked position. A reverse movement of the key will move the actuating member to locked position.

To lock the member from the inside of the vehicle, a finger operating member 90 is connected to one end of a push-pull member 91. The other end of the member 91 engages a locking arm 92.

A snap-over spring 93 engages the locking arm 92 and the flange 13 and serves to releasably hold the locking arm in locked or unlocked position.

The locking arm 92 has tongues 94 bent at right angles thereto which are bent to surround the tubular portion 50 on the actuating member. The portion 94 has inwardly directed end members 95 which engage the open ends of the end portion 50 as shown in Fig. 5, to thus form a loose connection to allow axial movement therethrough.

The construction is such that when the locking arm is moved downwardly the actuating member 48 will be moved to locked position and when the locking arm is raised the actuating member 48 will move to unlocked position.

In order to provide for coincidental locking of the doors, a shaft 100, which carries a coincidental roller 101 at its free end, has its inner end secured to the tongues 94 previously described as by welding at 94', Fig. 5.

The strike 17 coacts with a dovetail member 105 which is mounted on the door. The dovetail member includes a body 106, having a lower wedge member 107 bent therefrom and formed up to form a body having an inclined plane 108 and an integral bottom 109 with a flange 110 integral with the bottom. The body includes upper wedge members 111 and 112, each of which includes planar faces 113 and 114 and tops 115 and 116, which are connected to integral flanges 117 and 118. The entire wedge member is made of a one piece stamping and is held in place by fastening members 120.

The strike 17 has upper inclined face portions 121 and 122, which engage the planar face portions 113 and 114. The strike also has a dovetail wedge member 125 slidably mounted thereon. The wedge member is held in place by a plate 126 secured to the strike and is prevented from moving laterally by a longitudinally extending groove 127. A spring 128 normally urges the wedge member 125 into position.

To provide for coincidental locking of doors on the same side of the vehicle and on opposite sides of the vehicle, the pillar 19 is provided with a coincidental locking control member 130 which has upper and lower wings 131 and 132 at each end of its body 134. A pair of tongues 135 on the body extend through a slot (not shown) in the pillar 19 and are accessible from within the vehicle for movement up and down to effect the locking and unlocking action.

The control member 130 is mounted on a shaft 137 which is supported in brackets, not shown, secured to the inside of the pillar. The wings with the integral connecting body 104 serve to coincidentally lock adjacent doors.

5 Doors on opposite sides of the vehicle may be coincidentally locked as by a Bowden wire 140 which is suitably secured to the control members 130. To cause simultaneous action the Bowden wire is coupled to one control member 130 at the upper side thereof and the other end of the Bowden wire is connected to the other control member on the lower side thereof. Thus control members on opposite sides of the car both simultaneously move in the same direction in moving to locked and unlocked positions.

10 15 In order to provide safety means which would prevent thoughtless or accidental operation of the release means to open the door while providing ready access in an emergency, the dog 23 is provided with a tongue 150 which loosely fits in an eye 151 in the core 152 of a solenoid

20 153 which is shown as mounted on a bracket 154 secured to the base 11. Leads 155 and 156 may extend across the door hinge as shown in Craig Patent No. 2,204,208, granted June 11, 1940 to a source of current 157 and to a circuit closer 158 which includes an arcuate ring 159 connected to the lead 155, and a pointer 160 connected to the lead 156 and in contact with the ring 159. The pointer 160 is controlled by a speed actuated member, for example a speedometer on the vehicle.

25 When the vehicle is at rest the pointer engages a stop member 161 and no current flows to the solenoid so that the core 152 may be readily moved out as the dog 23 is rocked. When the vehicle is in motion the pointer 160 will close the circuit 159, thereby energizing the solenoid. A heavy force will then be required to actuate the inside control member on the push button to open the door.

30 35 Thus it will be seen that the door may be readily opened under light finger tip pressure when it is safe to do this, and that the door can be opened when it is unsafe to do so by the application of a heavy force.

The solenoid core 152 may have a head 165 thereon which engages a spring 166 to normally urge the solenoid core inwardly. The spring 166, however, may be omitted and the dog spring 25 may serve the double purpose of urging the dog and the solenoid core to the position shown 40 45 in Fig. 1.

In Figs. 11 and 12 modification of the invention is shown where in a coincidental locking shaft 100' having a roller 101' is secured as by welding 175, Fig. 12, to a connecting member 176 having bent up arcuate tongues 177 which surround the portion 51' of the locking member 48'. The shaft 100' is adapted to travel in aligned vertical slots 178 and 179 in the base 11' and the door 12' to thus prevent lateral movement of the connecting member 176.

50 55 A forwardly projecting tongue 72' from the lock core extends through a slot 180 similar to the slot 79 in a bent up portion 181 in the connecting member 186, and thence through a slot 79' in the left end of the actuating member 48' (Fig. 11) to engage an abutment 182 on the actuating member 48'.

The connecting member 176 engages a flat portion 183 on the locking member 48' to thus prevent relative rotation thereon.

60 65 Thus it may be seen that rotation of the tongue 72' will cause the connecting member 176 to be rocked thus rocking the shaft 100' to effect coincidental locking of the doors of the vehicle.

Having thus described my invention, I claim:

70 75 1. In a vehicle door lock, a bolt movable to engaged and released position, a dog normally preventing release movement of the bolt, an actuating member, means mounting the actuating member for rotation to locked and unlocked position and for axial reciprocation to and from dog releasing position, said actuating member including an operating portion adapted, when the actuating member is rotated to unlocked position, to rock the dog when the actuating member is moved axially, said operating portion being ineffective to rock the dog when the actuating member is moved axially while it is rotated to locked position, an inside lock member adapted to rock said actuating member to locked or unlocked position, means to hold said actuating member in either locked or unlocked position, inside means operable to release the dog, outside means operable to shift the actuating member axially to release the dog, and rotary lock controlled means coaxial

80 85 85

with the actuating member and accessible from without the vehicle for rotating the actuating member to and from locked position.

2. In a vehicle door lock, a bolt movable to engaged and released position, a dog normally preventing release movement of the bolt, an actuating member, means mounting the actuating member for rotation to locked and unlocked position and for axial reciprocation to and from dog releasing position, said actuating member including an operating portion adapted, when the actuating member is rotated to unlocked position, to rock the dog when the actuating member is moved axially, said operating portion being ineffective to rock the dog when the actuating member is moved axially while it is rotated to locked position, an inside lock member adapted to rock said actuating member to locked or unlocked positions, means to hold said lock member and said actuating member in either locked or unlocked position, inside means operable to release the dog, outside means operable to shift the actuating member axially to release the dog, rotary lock controlled means coaxial with the actuating member and accessible from without the vehicle for rotating the actuating member to and from locked position, and means operable when the dog is rotated while the actuating member is unshifted axially and is rotated to locked position to rotate the actuating member to unlocked position.

3. In a vehicle door lock, a rotary bolt, said bolt having a ratchet thereon, a dog engaging the ratchet to normally prevent rotation of the ratchet and bolt, an actuating member, means mounting the actuating member for rotation to locked or unlocked position and for axial reciprocation to and from dog releasing position, said actuating member including an operating portion adapted, when the actuating member is rotated to unlocked position, to rock the dog when the actuating member is moved axially, said operating portion being ineffective to rock the dog when the actuating member is moved axially while it is rotated to locked position, inside means to rock the actuating member to locked or unlocked positions, means to hold said actuating member in either locked or unlocked position, means to shift the actuating member axially to release the dog, lock controlled means accessible from without the vehicle for rotating the actuating member to and from locked position, and means operable when the dog is rotated while the actuating member is unshifted axially and is rotated to locked position to rotate the actuating member to unlocked position, and means to prevent rotary movement of the actuating member to unlocked position when the actuating member is shifted axially while the actuating member is rotated to locked position and the ratchet is rotated.

4. In a vehicle door lock, a base having a flange thereon, a rotary bolt on the base, said bolt having a ratchet thereon, a dog engaging the ratchet to normally prevent rotation of the ratchet and bolt, an actuating member, means mounting the actuating member for rotation to locked and unlocked position and for axial reciprocation to and from dog releasing position, said actuating member including an operating portion adapted, when the actuating member is rotated to unlocked position, to rock the dog when the actuating member is moved axially, said operating portion being ineffective to rock the dog when the actuating member is moved axially while it is rotated to locked position, an inside operated lock member on said flange engaging said actuating member to rock the latter to locked or unlocked positions, means to hold said lock member and said actuating member in either locked or unlocked position, means to shift the actuating member axially to release the dog, lock controlled means accessible from without the vehicle for rotating the actuating member to and from locked position, and means operable when the dog is rotated while the actuating member is unshifted axially and is rotated to locked position to rotate the actuating member to unlocked position, and means to prevent rotary movement of the actuating member to unlocked position when the actuating member is shifted axially while the actuating member is rotated to locked position and the ratchet is rotated.

5. In a vehicle door lock, a bolt movable to engaged and released position, a dog normally preventing release movement of the bolt, an actuating member, means mounting the actuating member for rotation to locked and unlocked position and for axial reciprocation to and from dog releasing position, said actuating member including an operating portion adapted, when the actuating member is

rotated to unlocked position, to rock the dog when the actuating member is moved axially, said operating portion being ineffective to rock the dog when the actuating member is moved axially while it is rotated to locked position, an inside lock member adapted to rock said actuating member to locked or unlocked positions, means to hold said lock member and said actuating member in either locked or unlocked position, inside means operable to release the dog, outside means operable to shift the actuating member axially to release the dog, lock controlled means accessible from without the vehicle for rotating the actuating member to and from locked position, and means operable when the dog is rotated while the actuating member is unshifted axially and is rotated to locked position to rotate the actuating member to unlocked position, and means to prevent rotary movement of the actuating member to unlocked position when the actuating member is shifted axially while the actuating member is rotated to locked position and the ratchet is rotated.

6. In a vehicle door latch, a rotary bolt for the door movable to engaged and released positions, a dog normally preventing release movement of the associated rotary bolt, an actuating member for releasing the bolt, means mounting the actuating member for rotation to locked and unlocked position and for axial reciprocation to and from dog releasing position, and means whereby the actuating member, when unlocked and moved axially, will rock the dog, said last mentioned means being ineffective, when locked and moved axially, to rock the dog, an inside lock member adapted to rock said actuating member to locked or unlocked position, inside means operable to release the dog, outside means operable to shift the actuating member axially to release the dog, and rotary lock controlled means coaxial with the actuating member and accessible from without the vehicle for rotating the actuating member to and from locked position.

7. In a door lock, a base adapted to engage the end of a door, said base having a flange arranged at right angles thereto and adapted to engage the inner wall of a door, a bolt pivoted on the base on an axis which is perpendicular to the base, a ratchet rigid with the bolt, bolt holding and releasing means engaging the ratchet for holding the bolt in engagement with a strike, an actuating member having a shoulder thereon, means mounting the actuating member for a movement to and from a locked position and also for movement towards said flange to release the bolt, said holding and releasing means including an arm which has a portion which is disposed out of the path of the shoulder on the actuating member when the actuating member is in its locked position, said holding and releasing means portion being disposed adjacent to and in the path of said actuating shoulder when the actuating member is in unlocked position, a locking member movable on said flange, said locking member including a planar body portion, means operable to hold the locking member in either locked or in unlocked position, means accessible from within the vehicle for moving the locking member from locked to unlocked position and vice versa, the actuating member and the locking member having slidably interengaging parts disposed adjacent to said flange whereby the locking member and the actuating member move together to and from locked position and the actuating member moves relative to the locking member to free the bolt holding and releasing means when the actuating member is moved to bolt releasing position while the locking member is in unlocked position and said actuating member being ineffective to release the bolt holding and releasing means when it is moved to bolt releasing position while the locking member is in locked position, means for moving the actuating member towards said flange to bolt releasing position, a crank, means pivotally mounting said crank on said flange, said holding and releasing means including an ear directed towards said flange, said crank including an arm having a free end engaging said ear, remote control means within the vehicle for rocking the crank whereby the crank arm moves said ear to thereby move the holding and releasing means to bolt releasing position, said actuating member including a second shoulder engageable with a second portion of the holding and releasing means when the actuating member is in locked position and is in non-bolt-releasing position and operable when the bolt is turned by engagement with a strike

to restore the actuating member to unlocked position, said shoulder being disposed so that it is out of the path of the last mentioned holding and releasing means portion and being ineffective, when the actuating member is in locked position and is in bolt releasing position and the bolt is turned by engagement with a strike to move the actuating member to unlocked position.
